(57) **CLAIM**

The ornamental design for an oral care implement accessory, as shown and described.

DESCRIPTION

FIG. 1 is a front left perspective view of an oral care implement accessory according to the new design;

FIG. 2 is a front right perspective view thereof;

FIG. 3 is a rear right perspective view thereof;

FIG. 4 is a rear left perspective view thereof;

FIG. 5 is a front view thereof;

FIG. 6 is a rear view thereof;

FIG. 7 is a left side view thereof;

FIG. 8 is a right side view thereof;

FIG. 9 is a top view thereof; and,

FIG. 10 is a bottom view thereof.

The outermost, centrally located broken line on the circular bristle carrier represents the bounds of the claim and forms no part thereof and all of the other broken lines illustrate portions of the oral care implement accessory that form no part of the claimed design.

1 Claim, 5 Drawing Sheets
